UNITED STATES PATENT OFFICE.

HUGO H. HANSON, OF BOSTON, MASSACHUSETTS, ASSIGNOR TO EASTERN MANUFACTURING COMPANY, OF BOSTON, MASSACHUSETTS, A CORPORATION OF MASSACHUSETTS.

METHOD AND APPARATUS FOR DRYING PAPER.

Application filed June 9, 1922. Serial No. 566,972.

To all whom it may concern:

Be it known that I, HUGO H. HANSON, a citizen of the United States, residing at Boston, in the county of Suffolk and State 5 of Massachusetts, have invented new and useful Improvements in Methods and Apparatus for Drying Paper, of which the following is a specification.

In the manufacture of high grade writing 10 paper such as bond, ledger, and linen finish paper, it has been customary to dry the paper, after the sizing operation, in lofts, where the sized sheets, arranged in packets, are hung over poles for some hours. This is 15 a slow process, non-continuous, and produces a pronounced curvature along the median line of each sheet where it is supported by the pole, but gives otherwise desirable results since the paper is not under restraint during 20 the drying operation so that it may shrink and produce a strong paper of desirable cockled surface.

Various attempts have been made to dry 25 the paper in a web by a continuous process, one of these, which is quite successful, being disclosed in the patent application of Hugo H. Hanson and Wilfred A. Wylde for method of and apparatus for drying paper, filed January 26, 1921, Serial Number 440, 30 173. In the machine disclosed in this application the paper is passed in the form of a continuous web over a plurality of horizontal rows of rollers in a drier casing, which are driven at progressively decreasing 35 speeds, the decreasing speed of the rolls allowing for the shrinkage of the paper as it dries so that it may be under substantially no restraint as it passes through the drier. With this apparatus the process is rendered 40 continuous, it being possible to utilize sufficient heat without damage to the paper to complete the drying operation for any portion of the paper within one minute. It is found, however, that the paper weaves back 45 and forth as it passes through this apparatus, so that it is wound or reeled irregularly after leaving it. It is usual to allow about one inch trim for the edges of a web of paper, but as this weaving or tracking effect 50 is sometimes as much as six inches, a trim of this amount might be necessary in some cases to avoid the production of narrow sheets during the subsequent slitting and cutting operations.

The cause of this weaving or tracking may 55 be explained by comparing the paper web to an endless belt passing over pulleys. If the pulleys are uncrowned and one side of the belt is a little longer than the other, the belt will run off the pulley at the shorter 60 edge where the tension is greater. As the paper is made on a paper machine, it is almost certain to have a longer and a shorter edge because of the different drying conditions in the drying cylinders, a more permanent stretch being produced on the faster drying edge of the paper. The paper on the paper machine would therefore tend to travel toward the opposite side of the paper machine, but is prevented from doing so 65 by the tension on the web which is sufficient to stretch the shorter edge to cause the paper to run true. When the tension is relieved the elasticity of the fibers causes this 70 more highly stretched edge to contract so 75 that the complete web still has a longer and a shorter edge.

In the continuous loft, as disclosed in the application above referred to, there can be 80 no stretch since the paper must be dried under as little restraint as possible, so that there is a definite tendency of the paper to travel toward the shorter edge. If this 85 tendency were constant, it might readily be provided for by setting over the reel a corresponding amount. It is not constant however.

After considerable experimentation it has been discovered that the weaving is caused 90 by variations in the slackness of the web, the less the slack the less the lateral travel and vice versa. The variation in slackness is caused by variations in shrinkage of the web during its travel through the drier due 95 to many variable conditions, such as changes in the amount of moisture in the paper as it comes from the paper machine, changes in the amount of size picked up in the sizing tub, changes in temperature inside the loft and variations in air currents 100 and humidity. These and other causes are too difficult of sufficiently accurate control for the practical elimination of weaving.

This invention therefore provides a 105 method and apparatus by which the amount of slack may be mechanically controlled within such limits as to insure a sufficiently constant lateral position of the issuing web.

For this purpose the slack is caused to be localized so that its extent may be observed, whereupon the relative speeds of the supporting and feed rollers may be regulated to retain the amount of slack within the desired limits.

For a more complete understanding of this invention, reference may be had to the accompanying drawings which illustrate an embodiment thereof in which

Figures 1 and 1^a represent a side elevation of the drier loft, part of the side wall being removed, together with the dry end of a paper machine and a sizing tub, the parts being shown somewhat conventionally.

Figures 2, 3, and 4 are diagrammatic views of the driving mechanism for the upper, intermediate and lower tiers of rollers showing the slack indicating mechanism.

Figure 5 is a diagrammatic detail of the driving mechanism.

Referring to Figure 1, at 1 are represented a pair of drying rolls at the dry end of the paper machine. At 2 is represented a sizing tub through which the web of paper shown in broken lines at *w* passes from the paper machine and where the size is picked up. From this tub the paper web passes between a pair of rolls 3, over a guide roll 4, and into the end of the continuous loft or drier through a narrow slot in the end wall thereof. The paper first passes over a feed roller 5 and then over a series of feed rollers arranged in groups, this being indicated for the top tier in Figure 2, the first group comprising those marked 6, the second group at 7 and the third group shown at 8. Beyond the group 8 the paper, as shown, passes over an end roll 9 and then passes back beneath the upper tier of feed rollers over a lower tier; the grouping of which is shown in Figure 3. This grouping comprises a series 10, the second series 11, and the third series 12. At the end of the series 12 is positioned a large roller 13 over which the paper passes down to the lowest tier, the grouping of which is shown in Figure 4. This grouping comprises three series of rollers 14, 15, and 16. After leaving the group 16 the paper passes under a guide roller 17, then over a pair of winding feed rollers 18 and to the reeling mechanism shown at 19, the winding rollers 18 being used to apply tension to the web as it is reeled by the reeling mechanism. While as shown the feed rollers are arranged in three tiers, this is merely for convenience in order to shorten up the mechanism. They could, if desired, be in a single tier or in any number desired.

In Figures 1 and 1^a are shown a series of blower fans 20 by means of which currents of heated air are passed over the paper wet

while supported on various tiers of rollers, details of this mechanism not being herein further described, since they are fully shown and described in the application above referred to. The groups of rollers of the different tiers are driven with relatively adjustable speeds, there being shown for this purpose in each of Figures 2, 3, and 4, a shaft 30 extending longitudinally of the machine, this shaft being driven as shown in Figure 2 through a pair of belted cone pulleys 31 from a main power shaft 32. The roller 5 at the entrance to the loft is driven at a constant speed relative to the shaft 32, it being shown as driven by bevelled gears from the driving cone pulley 31.

The first set of feed rollers 6 are shown as driven by means of suitable gearing through a jack shaft 32 belted at 33 to a pulley on the shaft 30. The rollers 7 as shown are driven at a somewhat lower speed through a shaft 34 geared to the shaft 30 and belted by a belt 35 on the shaft of one of the rollers 7, the other rollers being driven therefrom. The group 8 is shown as driven through a variable speed mechanism comprising a pair of belted cone pulleys 36 from the shaft 30. The group 10 of the intermediate tier is also driven through these same variable speed pulleys, but preferably at a lower rate of speed than the group 8. The group 11 is shown as being driven from the shaft 34, being belted therefrom by the belt 37. These rollers are driven at a lower speed than the group 7 and also lower than the group 10. The group 12 is shown as driven through a variable speed transmission comprising cone pulleys 38 at a lower speed than the group 11. The group 14 is also driven from this same variable speed mechanism. The group 15 is also belted to the shaft 34 by a belt 39 to be driven at a lower speed than the group 14 or the group 11. The group 16 is driven through a variable speed mechanism comprising cone pulleys 40 actuated by the shaft 30 and which also drives the winding rolls 18.

Preferably the groups of rollers are driven at a slightly higher rate than the speed of movement of the paper, though the end pulleys 5, 9, 13, and 18 which act more effectively to impart driving impulse to the paper should be driven at the speed at which it is desired to drive the paper. In this apparatus, however, it may be seen that the relative speeds of driving of the rollers may be regulated according to the speed of drying, to permit the paper to shrink while substantially unrestrained, it being under comparatively slight tension by the feeding mechanism.

In order to determine the slackness of the paper, a mechanism has been provided for concentrating the slackness at a single point in the form of a loop, the size of which may

be readily observed by the operator so that the relative speeds of the various groups of rollers may be adjusted to cause this loop to remain of practically constant size. For this purpose, in the construction shown, jets of air are employed to be projected against the web of paper to form a loop therein between a pair of rollers as at 1 1' of Figure 1. Such a jet is shown in Figure 2 at 50, comprising a pipe extending across the web substantially parallel to a pair of rollers 8 and between them, and having a slot in the side facing the web. A similar pipe is shown at 51 in Figure 3, extending across the web between the groups of rollers 10 and 11. Any suitable means (not shown) may be used to supply air under pressure to these pipes, supply pipe 500 and 510 leading therefrom to the jets 50 and 51 being indicated. Since most of the drying effect occurs at the upper and intermediate tiers, means for localizing the slack are shown as applied to these tiers only, though such means might be applied wherever desired.

Opposite the ends of these air pipes 50 and 51 the loft casing is preferably provided with a window as shown at 52 in Figure 1 so that the size of the loop, or the depth to which it extends below the plane of the top of the feed rollers may be readily observed by the operator, who may adjust the relative speeds of the groups of rolls to produce a nearly constant size of loop, so producing a substantially constant amount of slackness in the paper. By adjusting the rate of travel of the various rolls in conformity with the size of the loop in this manner, it has been found possible to control the extent of side travel of the web as it passes through the machine to hold it at a substantially constant value so that weaving is eliminated.

Having thus described an embodiment of this invention it should be evident that many modifications and changes might be made therein without departing from its spirit or scope as defined by the appended claims.

I claim:

1. The method of preventing weaving of a paper web traveling continuously in a path, while mechanically substantially unrestrained, through a drying chamber, which consists in relatively adjusting in different portions of the length of said chamber the rate of feed of said web.
2. The method of controlling the lateral travel of a paper web traveling continuously in a path through a drier casing while mechanically substantially unrestrained, which consists in gathering the slack of said web at a point along its length in said drier, observing the amount of said slack, and regulating the relative speed of feed in different portions of said casing in ac-

cordance with such observations to control the amount of said slack.

3. The method of preventing weaving of a paper web traveling continuously through a drier casing having a series of driven rollers therein on which the web is supported and by which it is fed substantially otherwise unrestrained, which comprises gathering the slack of said web in a loop between a pair of rollers and regulating the relative speed of rotation of said rollers so as to maintain said loop of a substantially constant size.

4. The method of preventing weaving of a paper web passing continuously through a drier casing having a series of driven rollers therein on which the web is supported and by which it is fed substantially otherwise unrestrained, which comprises directing a jet against said web between a pair of rollers to gather the slack of said web into a loop, and regulating the relative speed of rotation of said rollers so as to maintain said loop of a substantially constant size.

5. The method of controlling the lateral position of a continuous paper web issuing from a drier in which it is supported without substantial restraint, which comprises varying the relative speed of travel of said web along its path within said drier.

6. The method of controlling the lateral position of a continuous paper web issuing from a drier in which it is supported without substantial restraint, which comprises controlling the amount of slack in said web within said drier.

7. A drier comprising a casing having a series of rollers for supporting a continuous web passing through said casing, means for driving said rollers at variable relative speeds to feed said web in substantially unrestrained condition through said casing, and means for concentrating slack in said web between a pair of adjacent rollers in a loop to indicate to an observer the amount of such slack.

8. A drier comprising a casing having a series of rollers therein for supporting a continuous web passing through said casing, means for driving said rollers at variable relative speeds to feed said web in substantially unrestrained condition in said casing, and means for indicating the amount of slack in said web within said casing.

9. A drier comprising a casing having a series of rollers therein for supporting a continuous web passing through said casing, means for rotating said rollers at variable relative speeds to feed said web in substantially unrestrained condition through said casing, a pipe extending laterally of said web and having a slot directed there toward between a pair of adjacent rollers, and means for supplying air to said pipe to

blow said web between said adjacent rollers to localize slack therein in a loop.

10. A drier comprising a casing having a series of rollers therein for supporting a continuous web passing through said casing, means for rotating said rollers at variable relative speeds to feed said web in substantially unrestrained condition through said casing, a pipe extending laterally of said web and having a slot directed theretoward between a pair of adjacent rollers, means for supplying air to said pipe to blow said web between said adjacent rollers to localize slack therein in a loop, and a window in said casing through which the size of said loop may be observed.

11. A drier comprising a casing having a plurality of series of rollers therein for successively supporting and feeding a web through said casing, means for driving said rollers at differentially adjustable speeds whereby said web may be fed in substantially unrestrained condition, and means for localizing the slack of said web on certain of said series whereby the amount of slack may be determined.

12. A drier comprising a casing having a plurality of series of rollers therein for successively supporting and feeding a web through said casing, means for driving said rollers at differentially adjustable speeds whereby said web may be fed in substantially unrestrained condition, and means for forming a loop in the web between adjacent rollers of certain of said series to take up slack in the web.

13. A drier comprising a casing having

a plurality of series of rollers therein for successively supporting and feeding a web through said casing, means for driving said rollers at differentially adjustable speeds whereby said web may be fed in substantially unrestrained condition, means for forming a loop in the web between adjacent rollers of certain of said series to take up slack in the web, and means by which the amount of such slack shown by the length of loop may be observed.

14. A drier comprising a casing having a plurality of series of rollers therein for successively supporting and feeding a web through said casing, means for driving said rollers at differentially adjustable speeds whereby said web may be fed in substantially unrestrained condition, and means for blowing against said web between adjacent rollers of certain of said series to localize the slack of said web in a loop between said rollers.

15. A drier comprising a casing having a plurality of series of rollers therein for successively supporting and feeding a web through said casing, means for driving said rollers at differentially adjustable speeds whereby said web may be fed in substantially unrestrained condition, means for blowing against said web between adjacent rollers of certain of said series to localize the slack of said web in a loop between said rollers, and means by which the length of said loop may be observed.

In testimony whereof I have affixed my signature.

HUGO H. HANSON.
